UNITED STATES PATENT OFFICE.

ERNEST L. REGUIN, OF SACRAMENTO, AND THOMAS J. KINGSTON, OF SAN FRANCISCO, CALIFORNIA.

REVERSIBLE WINDOW-SASH.

SPECIFICATION forming part of Letters Patent No. 425,146, dated April 8, 1890.

Application filed October 26, 1889. Serial No. 328,296. (No model.)

To all whom it may concern:

Be it known that we, ERNEST L. REGUIN, of the city of Sacramento, in the county of

Sacramento, State of California, and THOMAS J. KINGSTON, of the city and county of San

Francisco, State aforesaid, have invented an Improvement in Reversible Window-Sashes; and we hereby declare the following to be a full, clear, and exact description thereof.

10 Our invention relates to that class of window-sashes which are pivoted by their stiles to the casing, whereby they are adapted to be reversed in order to allow the outside of the glass to be reached and cleaned with convenience.

15 Our invention consists in the novel construction and arrangement of the sash-frame, the means for turning the sash and locking it in position when turned, the means for tightening it, and other details of construction, hereinafter fully described, and specifically pointed out in the claims.

20 Referring to the accompanying drawings, Figure 1 is an elevation of a window frame and sash, a portion of one side being broken away and shown in section. Fig. 2 is a horizontal section. Fig. 3 is a vertical section of a portion of the sash-frame, slide-bar, and bearing-plate F.

25 A is the usual casing of a window, having the inside and outside stops or beads a and the parting-strips a'.

30 B is the window-sash, and C are independent slide-bars, which intervene between the stiles b of the sash and the grooves of the window-casing. The sash-stiles b are formed with slight tongues b' and the adjacent faces of the slide-bars C are formed with corresponding grooves c, so that the two fit together 35 by a tongue-and-groove joint. Secured to the sash-stiles on each side at about their centers are the pivot-pins D. These are securely fastened to the stiles, and they pass through holes c' in the slide-bars, whereby the sash-frame 40 is pivoted to said slide-bars and may be turned between them. In the pivot-pins is made an encircling groove d and a second encircling groove d'. These grooves, though they may be formed in any suitable manner, 45 are preferably formed in the shape of a double

cone, as shown, whereby they have beveled surfaces adjacent to one another, thereby allowing them to slip by the set-screws, when loosened, with facility.

50 In the slide-bars C are seated the set-screws E, the inner ends of which are adapted to bear within either of the grooves of the pivot-pins. Fitted upon the ends of the pivot-pins are the bearing-plates F, which rest against a shoulder d² on said pins, so as to hold 55 them out to place in constant contact with the bottom of the window-casing grooves. These plates extend out beyond the back surface of the slide-bars and bear constantly in the bottoms of the grooves of the window- 60 casing. They are separated from the slide-bars sufficiently to permit the latter to have their necessary side movement to or from the sash-frame. This separation may be effected in any suitable manner, though in order to 65 have the slide-bars fit the casing as snugly as may be consistent with their side movement we prefer to seat the bearing-strips partially in chambers c², made in the back surface of the slide-bars, said chambers being large and 70 deep enough to freely fit and play over the bearing-strips as the bars are moved in and out.

75 G are frictional binding-strips, which are pivoted to the slide-bars at their upper and lower ends, the ends of said strips being turned at right angles and adapted to bear 80 against the window-casing, being held in this position by their other ends fitting by means of a small hole g over a small pin or stud g² 85 in the slide-bar.

90 The construction will be better understood by describing the operation of the window-sash, which is as follows: When the sash is in its place in the window-casing, the slide-bars C are moved up close to the stiles of the window-sash, so as to make a tight tongue-and-groove joint therewith, and they are held firmly in this position by means of the set-screws E, which are turned in so as to bind 95 tightly in the first groove of the pivot-pins D. In this position it is obvious that the sash cannot be released from the slide-bars, as the tongue-and-groove joint between them holds them together. Consequently, the slide-bars 100

must be moved out sidewise away from the sash in order to relieve the sash of the tongue-and-groove joint. The construction, therefore, must be such as to allow the slide-bars sufficient side play in the window-frame to free the sash; but in allowing this side play it is necessary that some bearing be provided, so as to constantly hold the entire sash closely in the window-casing and prevent it from wabbling. This result is effected by the bearing-plates F on the ends of the fixed pivot-pins D, which, as before stated, project beyond the back surface of the slide-bars and fit directly and constantly against the bottoms of the grooves of the window-casing, thereby holding the entire device snugly in its seat. Now, in order to reverse the window-sash the set-screws E are turned back, so as to free their inner ends of the groove of the pivot-pins D. Then both slide-bars C are moved bodily sidewise on the pins away from the stiles of the sash until the tongue-and-groove joint is broken, whereby the sash may be readily turned, its pivot-pins turning in the slide-bars. This movement of the slide-bars is on the fixed pivot-pins, their chambers c^3 in their back surfaces playing freely over the stationary bearing-strips F, which do not interfere with the movement of the slide-bars. When the window is turned to any position desired, it can be held in that position by turning in the set-screws again, so that they fit their ends into the second grooves of the pins.

35 The weights W are suspended by cords w, which are attached to the slide-bars of the window-sash. The object of the frictional binding-strips G is not only to prevent any looseness in the sash, but also, by bearing against the window-casing, to hold with greater security the slide-bars and the stiles of the window-sash together.

We are aware that window-sashes have been pivoted on each side, whereby they are adapted to be reversed, and we are also aware that slide-bars have been mounted in the grooves of the window-casing, and to these bars the sash-frame proper has been pivoted, and we do not, therefore, claim such, broadly; but

45 50 What we do claim as new, and desire to secure by Letters Patent, is—

1. In combination with a window-frame having the usual grooves, the window-sash having fixed to its sides the pivot-pins D, the independent and laterally-movable slide-bars fitted and movable upon the pivot-pins of the sash and seated in the grooves of the window-casing, and set-screws in the slide-bars bearing upon the pivot-pins of the sash, whereby the movable slide-bars may be held to the sash and the sash itself held in any position to which it is turned, substantially as described.

2. In a reversible window-sash, the combination of the sash-frame having the fixed side pivot-pins, the independent and laterally-movable slide-bars seated in the window-cas-

ing grooves and fitted and movable upon the side pins of the sash-frame, a tongue-and-groove joint between the slide-bars and the sash-frame, and set-screws in the slide-bars bearing on the pins of the sash-frame, whereby the bars and frame are held together and the sash-frame held in any inclination to which it may be turned, substantially as described.

3. In a reversible window-sash, the combination of the sash-frame having the fixed pivot-pins extending from its sides, said pins having the two encircling grooves, the independent and laterally-movable slide-bars seated in the grooves of the window-casing and fitted and movable upon the pins of the sash-frame, the tongue-and-groove joint between the stiles of the sash-frame, and the slide-bars and the set-screws in said slide-bars for bearing in either of the grooves of the pivot-pins, whereby the slide-bars are held to the stiles and the sash-frame held at any inclination to which it may be turned, substantially as described.

4. In combination with the window-casing having the usual sash-grooves, the sash-frame having the fixed pivot-pins extending from its sides, the independent and laterally-movable slide-bars mounted and movable on the pins of the sash-frame and seated in the grooves of the window-casing, set-screws in the slide-bars bearing upon the pivot-pins, and the bearing-plates F, mounted on the ends of the fixed pins of the sash-frame and projecting beyond and separated from the back surface of the slide-bars, whereby they travel in the bottoms of the grooves of the window-casing and hold the sash snug while permitting the lateral movement of the slide-bars, substantially as described.

5. In combination with the window-casing having the usual sash-grooves, the sash-frame having the fixed pivot-pins at each side, the independent and laterally-movable slide-bars fitted and movable upon said pins and mounted in the grooves of the window-casing, said bars having chambers in their back surfaces, set-screws in the slide-bars bearing upon the pivot-pins, and the bearing-plates F, mounted upon the ends of the pins and freely seated in the chambers of the slide-bars, said plates projecting from the back surface of said bars and bearing in the bottoms of the window-casing grooves, whereby they hold the sash snugly and allow the lateral movement of the slide-bars, substantially as described.

6. In combination with the window-casing having the usual sash-grooves, the sash-frame having the fixed side pivot-pins, the independent and laterally-movable slide-bars fitted and movable upon said pins and mounted in the grooves of the window-casing, said bars having chambers in their back surfaces, a tongue-and-groove joint between the slide-bars and sash-frame, set-screws in said slide-bars bearing on the pins of the sash-frame for holding said bars and frame together, and the bearing-plates mounted on the ends of the sash-frame pins and freely seated in chambers

in the back of the slide-bars, said plates projecting from the bars and bearing in the bottoms of the grooves of the window-casing, whereby a snug fit is made for the sash and the lateral movement of the slide-bars permitted, substantially as described.

7. In combination with the window-casing, the sash-frame having side pins, the independent and laterally-movable slide-bars, to which the sash-frame is pivoted by its pins, and the frictional binding-strips G, pivoted on the slide-bars and bearing against the window-casing, whereby the slide-bars and sash-frame are pressed together, substantially as described.

8. In combination with the window-casing, the sash-frame having side pins, the independent and laterally-movable slide-bars to

which said frame is pivoted by its pins, and the pivoted frictional binding-strips G, secured to the slide-bars and binding on the window-casing, said strips having holes engaging pins in the slide-bars, whereby they are held in position and may be released, substantially as described.

In witness whereof we have hereunto set our hands.
